UNITED STATES PATENT OFFICE.

OSKAR ANTON WIBERG, OF FINSPONG, SWEDEN, ASSIGNOR, BY MESNE ASSIGNMENTS,
TO AKTIEBOLAGET LJUNGSTRÖMS ÅNGTURBIN, OF STOCKHOLM, SWEDEN, A COR-
PORATION.

ELASTIC-FLUID TURBINE.

1,291,322.

Specification of Letters Patent. Patented Jan. 14, 1919.

Application filed July 19, 1917. Serial No. 181,623.

To all whom it may concern:

Be it known that I, OSKAR ANTON WIBERG, a subject of the King of Sweden, residing at Finspong, Sweden, have invented certain new and useful Improvements in Elastic-Fluid Turbines, of which the following is a specification.

The present invention relates to elastic-fluid turbines of the type comprising two rotors or blade wheels which rotate in opposite directions, and which have axially extending interleaving blade rings.

In connection with the operation of elastic-fluid turbines it is often desirable to extract elastic fluid from an intermediate stage for industrial purposes, or to admit low pressure fluid thereto from a separate source. In a turbine of the type referred to, however, this is not possible without special provisions, and the object of the present invention is to provide a new and improved arrangement and construction whereby elastic fluid may be extracted from such a turbine.

For a consideration of what I believe to be novel and my invention, attention is directed to the accompanying specification and the claims appended thereto.

In the drawing, Figure 1 is an axial sectional view of a part of a turbine illustrating my invention; Fig. 2 is a similar view of a second form which my invention may take, and Fig. 3 is a detail view of certain of the parts of Fig. 2.

In carrying out my invention, I provide in connection with the double rotary system of blade rings, *i. e.*, with the system which comprises the axially extending interleaving blade rings, two separate blade systems, one associated with each rotor, which separate blade systems are located after the double rotary system as regards the flow of actuating fluid, and I then extract elastic fluid from between such two separate blade systems or admit low pressure fluid thereto. The two separate blade systems may be either of the axial flow type, *i. e.*, provided with radially extending blades, or the radial flow type, *i. e.*, provided with axially extending blades. The pressure and hence temperature of the extracted elastic fluid will depend upon the relation between the number of blade rings in the double rotary system and the number in the two separate

blade systems, and may be varied by varying such relation.

Referring to the drawing, Fig. 1, 5 indicates a turbine casing, and 6 and 7 two turbine shafts which carry rotors 8 and 9. The rotors 8 and 9 have rings of interleaving blades 10 forming a double rotary blade system, the rotors rotating in opposite directions, as is well understood. 11 indicates suitable labyrinth packings which are situated between the outer surface of each rotor and the adjacent stationary disk carried by the turbine casing. The steam flowing radially outward between the rotors 8 and 9 exerts an axial thrust thereon tending to separate them; this is balanced by the opposing parts carrying the packing and through which steam flows. 12 indicates chests from which elastic fluid is admitted by passages 13 and 13^a to the blade rings. 14 indicates a motive fluid chamber arranged outside the rings of blades 10, the outer wall 15 thereof being formed by an annular stationary ring suitably supported on the casing 5. The chamber 14 is annular and serves to equalize the pressure of the streams issuing from the various short blade lengths in the radial flow system and it also serves as an equalizing chamber to distribute steam to the stationary device directing steam to the axial flow blade system. Further, the wall 15 serves to protect the outer casing from the effects of hot steam, it being noted that between the wall and the casing is an annular space filled with steam at exhaust pressure. Carried by the wall 15 are stationary blade or guide rings 16 and co-operating therewith are movable blade rings 17 carried by each of the rotors 8 and 9. In the present instance only one stationary blade ring and one rotating blade ring is shown in connection with each rotor, but it will be understood that a suitable number will be used as required to give the desired pressure and temperature as referred to above. 18 indicates the exhaust chamber of the turbine which is connected to a condenser in the usual manner. Communicating with the chamber 14 is a conduit 19 through which elastic fluid is extracted for commercial purposes. The conduit 19 may be provided with a suitable valve (not shown) for regulating the flow through it.

Referring now to the modification shown in Figs. 2 and 3, 20 indicates the turbine casing, 21 and 22 the shafts, 23 and 24 the rotors carried thereby, 25 the double rotary blade system, 26 the motive fluid chest, and 27, 27^a the passages leading therefrom to the blade rings. These parts correspond to the similar parts of Fig. 1. 28 indicates the chamber corresponding to chamber 14 of Fig. 1, from which elastic fluid is extracted for industrial purposes, and 29 the extraction conduit having a valve 30 therein. In the arrangement here shown, the outer wall of chamber 28 is formed by a wall of the turbine casing, and on each side of the chamber is a stationary ring 31 carrying, in the present instance, two rings of stationary blades 32, associated with which are two rings of rotating blades 33 carried by the adjacent rotor 23 or 24. In this arrangement a suitable valve mechanism is provided for controlling the flow of elastic fluid from chamber 28 to the vane system, comprising blades 32 and 33. In the present instance a ring valve is shown in connection with each system comprising the annular stationary ring 31 having spaced opening 35 therein, and a movable ring 36 having openings 37 therein. 38 is an operating link arranged to extend through the casing wall and connected to a projection 39 on the movable ring 36 by which it may be turned to bring the openings 37 into and out of registry with openings 35, or to some intermediate point. By this means the pressure within chamber 28 can be regulated and maintained constant under varying operating conditions.

My improved construction can also be employed to admit steam to the turbine from a low pressure source, as for example a non-condensing engine or the exhaust from a heating or cooking system.

In accordance with the provisions of the patent statutes, I have described the principle of operation of my invention, together with the apparatus which I now consider to represent the best embodiment thereof; but I desire to have it understood that the apparatus shown is only illustrative, and that the invention can be carried out by other means.

What I claim as new and desire to secure by Letters Patent of the United States, is,—

1. An elastic-fluid turbine comprising two blade wheels running in opposite directions, an inner radial flow blade system associated

with both said wheels, two outer axial flow blade systems associated one with each wheel, and a conduit connected at a point 60 between said radial and axial flow blade systems through which elastic fluid may be extracted or admitted.

2. An elastic-fluid turbine comprising two flow blade wheels running in opposite directions, an inner radial blade system associated with both said wheels, two outer axial flow blade systems associated one with each wheel, an elastic fluid equalizing chamber arranged between the radial flow and the 70 axial flow systems, and a conduit connected with said chamber through which elastic fluid may be extracted or admitted.

3. An elastic-fluid turbine comprising two blade wheels running in opposite directions, 75 an inner radial flow blade system associated with both said wheels, two outer axial flow blade systems associated one with each wheel and each consisting of stationary guide blades and rotating blades mounted on the turbine wheel, and a conduit connected at a point between said radial flow and axial flow blade systems through which elastic fluid may be admitted or extracted.

4. An elastic-fluid turbine comprising two 85 blade wheels running in opposite directions, an inner radial flow blade system associated with both said wheels, two outer axial flow blade systems associated one with each wheel, an equalizing chamber which receives 90 fluid from the radial flow system and discharges it to the axial flow system, a conduit connected to said chamber through which elastic fluid may be admitted or extracted, and means for regulating the passage of 95 elastic fluid to said outer blade systems.

5. An elastic-fluid turbine comprising two blade wheels running in opposite directions, an inner radial flow blade system associated with both said wheels, two outer axial flow 100 blade systems associated one with each wheel, an elastic fluid equalizing chamber provided between said radial flow and axial flow blade systems, a conduit communicating with said chamber through which elastic fluid may be admitted or extracted, and a rotatable ring valve arranged between said chamber and each of said axial flow blade systems for regulating the supply of elastic fluid to said axial flow blade systems. 105

In witness whereof, I have hereunto set my hand this 1st day of June, 1917.

OSKAR ANTON WIBERG.

It is hereby certified that in Letters Patent No. 1,291,322, granted January 14, 1919, upon the application of Oskar Anton Wiberg, of Finspong, Sweden, for an improvement in "Elastic-Fluid Turbines," errors appear in the printed specification requiring correction as follows: Page 2, line 65, claim 2, strike out the word "flow"; same page and claim, line 66, after the word "radial" insert the word *flow*; and that the said Letters Patent should be read with these corrections therein that the same may conform to the record of the case in the Patent Office.

Signed and sealed this 25th day of February, A. D., 1919.

[SEAL.]

F. W. H. CLAY,

Acting Commissioner of Patents.

Cl. 60--67.
